UNITED STATES PATENT OFFICE.

WILLIAM B. HUSSAR, OF ST. LOUIS, MISSOURI.

VEHICLE TRAFFIC SIGNAL.

Application filed August 10, 1923. Serial No. 656,683.

This invention relates to traffic signals for vehicles, and more particularly to a signal adapted to be applied to the front left fender to indicate "go", "left turn", "right turn" and "stop", and, it is a distinct and practical improvement to overcome certain practical objections to, and defects in, the present type of traffic signal.

The objects of the invention, are, first to provide a traffic signal which is manually actuated to indicate the forward and turning movements of a vehicle to traffic in front, rear, and to the sides of the vehicle; second, to electrically actuate the "stop" sign by actuating the brake pedal; third, to automatically return the "go" sign to signal position upon releasing the brake pedal; fourth, to provide a spherical rotor upon which the signal data is applied; fifth, to provide means to display the "stop" signal whether either the "go" or turning movements are being displayed, and, sixth, to provide means for illuminating the signal at night.

With the above and other objects in view, the invention consists in the novel features of arrangement and combination of parts and their equivalents, hereinafter more fully described and finally pointed out in the claims hereto appended.

Referring to the drawings forming a part of this specification, wherein like characters of reference denote similar parts throughout the several views:

Fig. 1, is a top plan view of a signal device embodying the features of my invention, the case thereof and the signal rotor being shown in sectional elevation.

Fig. 2, is a top plan view of the device applied to the front left mud guard of a vehicle.

Fig. 3, is a side elevation of the interior mechanism with the casing and signal rotor in sectional elevation.

Fig. 4, is a side elevation of the interior mechanism of the signal device, with the casing and rotor in sectional elevation and the electrical connection diagrammatically shown.

Fig. 5, is a front elevation of the device applied to a fender.

Fig. 6, is a detail showing part of the means for actuating the signal rotor.

In carrying out the aim of my invention, I employ a suitable metallic casing which is substantially spherical and which consists

of the rear section 1 and the front section 2 which are suitably united, as at 3. The rear section, or half of the casing, is provided with the side opening 4 which is closed by means of a suitable transparent cover plate 5 and the front section, or half of the casing is provided with the sight opening 6 which is closed by means of a suitable transparent closure plate 7.

Suitably fixed to and extending inwardly from opposite sides of the casing section 1, are a pair of opposed and aligned tubular arms 8 and 9. Arm 8 is longer than arm 9 and is provided at its inner end with a suitable socket 10 for holding an electric lamp 11.

12 indicates a suitable hollow spherical shaped rotor provided with the sleeves 13 and 14 for rotatably mounting the signal rotor upon the tubular supporting arms 8 and 9, respectively, as clearly shown in Fig. 1. A suitable coiled spring 15 is interposed between the supporting arm 9 and the rotor sleeve 14 and has one end thereof fixed to the arm 9 and the opposite end thereof fixed to the sleeve 14 for returning the rotor to any predeterminable signal position after displaying a stop signal.

A suitable solenoid 16 is suitably fixed to and supported by means of suitable bracket members 17, which bracket members 17 are suitably fixed to the tubular supporting arm 9. The solenoid is vertically disposed and is provided with an armature 18 directed into the solenoid from the top thereof. A suitable cross-arm 19 is fixed to the upper end of the armature 18 and extends to a point beyond the right side of the solenoid. The outer end of the arm 19 is directed downwardly to provide a plunger member 20 for imparting a partial rotation to the signal rotor whenever it is moved downwardly into contact with the teeth 21 of the ratchet wheel 22 which ratchet wheel is fixed to the inner end of the signal rotor sleeve 13 disposed to the right hand side of the solenoid. A suitable guide pin 23 is fixed at its upper end to the cross-arm 19 and directed downwardly therefrom with its lower end passing through an opening in a guide plate 24 which plate is preferably fixed to the upper end of the solenoid 16. A coiled spring 25 encircles the guide pin 23 and is disposed between the arm 19 and guide plate 24 for exerting upward pressure against the arm 19 to nor-

105
110

mally hold the arm and armature 18 in their uppermost position. An arm 26 having its outer end beveled, as at 27, is fixed to the upper end of the armature 18 and it is directed in an opposite direction to the cross-arm 19.

28 represents a suitable armature which is pivotally connected, as at 29, to suitable ears fixed to the solenoid 16. The armature 28 is vertically disposed to the left side of the solenoid 16 and has its upper end bent inwardly to provide the lock-lip or catch 30. A suitable flat spring 31, exerting outward pressure against the lower end of the armature 28 below the pivot point 29, normally holds the upper end of the armature in its innermost position, as clearly shown in Fig. 3. Disposed opposite the lower end of the armature 28 is a horizontally disposed electromagnet 32 which is suitably fixed to the lower end of the solenoid 16, as shown in Figs. 3 and 4.

As shown in Figs. 1 and 4, the reference characters 33, 34 and 35 represent an upper, a middle and a lower spring contact members separated by means of the insulated separators 36 and fixed to the upper end of a suitable bracket 37 which bracket is suitably fixed to the tubular supporting arm 8, as shown in Fig. 6. The middle spring contact member 34 is longer than the contact members 33 and 35 and the inner end thereof is disposed in the downward path of travel of the cross-arm 19 to be engaged thereby and depressed when the armature is drawn downwardly into the solenoid for breaking contact thereof with the upper contact member 33 and making contact with the lower contact member 35.

40 The mechanical means for rotating the signal rotor to indicate the movements of the vehicle, such as "go," "left turn" and "right turn" consists of a suitable peripherally grooved pulley 38 fixed to the rotor 12 intermediate the casing and the signal rotor, as shown in Fig. 1, the shifting lever 39 which is fixed to the grooved pulley 40, which pulley is pivotally connected as at 41 in a suitable case 42. The case 42 is suitably fixed to the steering post of a vehicle, or at some other convenient point within reach of the operator. A suitable flexible cable 43 is connected at one end to the lever actuated pulley 40, as shown in Fig. 1, and the opposite end thereof is connected to the pulley 38, as shown in Fig. 4, for rotating the signal rotor in either direction by means of the shifting lever 39. The inner end of the cable adjacent the pulley 38 passes through a tube 44 suitably fixed to the casing member 1 and is encircled by means of a coiled spring 45, one end of which engages the outer end of the tube 44 and the inner end engages a collar stop 46 fixed to the cable for taking up the slack in the cable engaging

the pulley 38 when the cable is moved toward the pulley 38, thus assisting the coiled spring 45 in movement of the rotor in that direction. There are three positions indicated upon the casing 42 to represent stopping places of the shifting lever 39, namely, "go," "left turn" and "right turn" and represented by the reference characters 47, 48 and 49, respectively.

75 The spherical signal rotor 12, which is in the form of a hollow inner shell, preferably made of two like sections suitably united, has its wall divided into twelve sections in the form of elongated circumferential sight openings represented by means of reference characters 50, 51, 52, 53, 54, 55, 56, 57, 58, 59, 60 and 61 which are backed by means of transparent closures 62 bearing the signal data "Go" "Stop," "arrows" representing left turn and "arrows" representing right turn. The signal data is displayed and is visible in pairs through the sight opening 6, as clearly shown by the signal data "Go—Go" in Fig. 4. Like signal data that is displayed through the front sight opening 6 is also displayed through the rear sight opening 4, excepting it is a single display of the signal data instead of in pairs, as the rear sight opening 4 is only half the length of the front sight opening 6, as shown in Figs. 1 and 2. Besides the signal data being arranged in pairs, there is also two sets of paired signals represented upon the signal rotor or globe, as will be readily understood by the reference to Fig. 4, wherein "S" stands for stop; "Go" stands for go; "LT" stands for left turn and "RT" stands for right turn. When the signal "Go" is visible through the front sight opening 6, the same signal is visible through the rear sight opening 4.

90 It will be observed that by arranging the sight openings 4 and 6, as shown, that vehicle traffic as well as pedestrians and traffic police can see the front signal data from either side of the device, as well as from the front due to the spherical shape of the signal rotor, as will be apparent from the arrows in Fig. 2. Also that the duplicate rear signal data is visible both from the rear and from the outer side, as represented by arrows in Fig. 2. In fact the signal displayed is visible either at night or in the day time within a radius of approximately two hundred and seventy degrees. The device is preferably mounted upon the left hand front mud guard represented by the reference character 63 in Figs. 2 and 5, but is also applicable to being applied to the side of the windshield, the radiator cap, or any other suitable elevated place toward the front of the vehicle.

105 The electrical connections and mechanism for controlling the device as a stop signal, will now be described.

110 The reference character 64 represents a

suitable battery and 65 the foot brake pedal of a vehicle which is connected to the movable contact member 66 of a suitable two-way switch 67 by means of suitable connection 68. The switch is provided with three terminals 69, 70 and 71. The terminals 69 and 71 are normally connected by means of the movable contact member 66.

A conductor 72 leads from one side of the battery to the switch terminal 69. A conductor 73 leads from switch terminal 70 to solenoid 16 and a conductor 74 leads from the solenoid to the upper spring contact member 33 which has one end normally in contact with the middle spring contact member 34 and 75 indicates a conductor leading from the middle contact member to the other side of the battery. This arrangement completes an electrical circuit through the solenoid whenever the foot pedal 65 is depressed causing the contact member 66 to break with terminal 71 and contact with terminal 70, thus energizing the solenoid and pulling the armature 18 down into same which causes the plunger 20 to engage one of the teeth of the ratchet and rotate the signal rotor one twelfth of a revolution in an upwardly direction, which would bring the stop sign into view behind the sight openings in lieu of the "go" signs, taking Fig. 4 as an example as illustrated, as the "go" signs are normally in view. The circuit is opened immediately upon the cross arm 19 striking the middle contact member 34 in its downward travel which causes the middle contact member to contact with the lower contact member 35. The solenoid is held in its lowermost position to prevent return rotation of the signal rotor 12 by means of the catch armature 28 engaging over the armature arm 26 and holding the armature 18 from upward movement through the medium of the coiled spring 25, as is evident from Fig. 3.

The moment that the foot pedal 65 is released and the contact member 66 engages the terminal 71, a new circuit is closed through the conductors 72 from the battery, contact member 66, a conductor 76 leading to the electromagnet 32, a conductor 77, the lower spring contact member 35, the middle contact member 34 and the conductor 75 to battery. The moment that this circuit is closed by releasing the foot pedal 65, the electromagnet is instantly energized attracting the lower end of the armature 28 thereby releasing the upper catch end thereof from the armature arm 26 thereby causing the armature 18 to raise through the spring 25 and break the contact between the middle contact arm 34 and lower contact arm 35 for opening the circuit and causing the middle contact arm 34 to again contact with the upper contact arm 33. The raising of the armature 18 and its plunger 20 permits the signal rotor to revolve back to its normal

position through the medium of the coiled spring 15 interposed between the signal rotor sleeve 14 and the supporting member 9.

In case the shifting lever should be moved to either point 48 or 49 to indicate right turn or left turn signs before the sight openings 4 and 6 and the foot pedal 65 should be depressed, the same actions would take place in displaying the stop signal before the sight openings just described when the "go" sign 75 was in view behind the sight openings 4 and 6.

To light the lamp 11 at night to illuminate the signal signs, I employ a conductor 78 leading from one side of the battery to one contact of the socket and provide the same with a switch 79 and I also provide a second conductor 80 leading from the other contact to the other side of the battery which will complete a closed circuit to the lamp 11 85 when the switch is closed.

It is apparent from the foregoing description that I employ a complete vehicle traffic direction signal which will display the turning and go signals which are manually controlled through a shifting lever and that combined with these signals are stop signal signs which are controlled electrically through the actuation of the foot brake pedal. 95

The many advantages of the herein described invention will readily suggest themselves to those skilled in the art to which it appertains.

I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall within the scope of the appended claims when fairly construed. 100

What I claim is:

1. In a traffic signal structure for application to the front of a vehicle, a casing having a sight opening extending across the entire front of the casing and having a sight opening extending across one half of the rear of the casing, a hollow globular rotor provided with a plurality of circumferentially disposed "go", "left turn", "right turn" and "stop" signal indicia mounted for rotation within said casing and normally positioned to simultaneously display the "go" signal indicia through the front and rear sight openings of the casing, said "stop" signal indicia being alternately arranged, manually actuated means for revolving the rotor in one direction for simultaneously bringing left turn signal indicia opposite the front 130

and rear sight openings of the casing, resilient means co-acting with the manually actuated means for rotating the rotor in the opposite direction for simultaneously bringing right turning signal indicia opposite the front and rear sight openings of the casing, electrically actuated means for revolving the rotor to a position to display the "stop" signal data from either "go", "left turn", or "right turn" signal positions and means for holding the rotor in said "stop" signal position and electrically actuated means for releasing the rotor from said "stop" signal position to permit of its rotation back to the signal position from which it was initiated.

2. In a traffic signal structure, a stationary casing having front and rear sight openings, a rotor shell mounted for rotation within the casing and provided with a plurality of circumferentially disposed "go", "left turn", "right turn" and "stop" signal indicia so arranged as to display like signal indicia through the front and rear sight openings of the casing simultaneously and normally positioned so as to display the "go" signal indicia, said stop signal indicia being alternately arranged, a shifting lever fixed at a convenient point adjacent the driver of a vehicle, flexible means connecting the rotor shell with said lever for revolving the rotor shell to a position to display one of the turn signals when the lever is moved in one direction, a coiled spring connected at one end to the rotor shell and at its opposite end to the casing for revolving the rotor shell to a position to display the other turn signal when the lever is moved in the opposite direction, a foot actuated pedal and an electrically actuated mechanism controlled through the medium of said foot pedal when depressed for revolving the rotor shell to a position to display the "stop" signal indicia and when released to return the rotor to the position from which it was initiated.

3. In a vehicle traffic signal structure, a separable hollow spherical casing having front and rear sight openings, a rotor mounted within said casing, a plurality of circumferentially disposed "go", "left turn", "right turn", and "stop" signal indicia, said rotor being positioned to normally display the "go" signal indicia and said "stop" signal indicia being alternately arranged, means for manually actuating said rotor to display simultaneously either "left turn" or "right turn" signals through the front and rear sight openings of the casing, electrical means actuated by the depression of a vehicle brake pedal for revolving the rotor to display the "stop" signal indicia through the front and rear sight openings, holding means for retaining the rotor against return movement while displaying the "stop" signals and electrical means for releasing the holding

means to permit the rotor to automatically return from its stop position to the position from which it was initiated.

4. In a vehicle traffic signal structure, a separable hollow spherical casing having front and rear sight openings, a rotor bearing a plurality of "go", "left turn", "right turn" and "stop" signal indicia mounted for rotation within said casing so as to display like indicia to the front and rear simultaneously, said rotor being positioned to normally display "go" signal indicia and having the "stop" signal indicia arranged alternately, means consisting of a flexible cable, a pulley fixed to the rotor to which one end of the flexible cable is connected and a shifting lever to which the opposite end of the flexible cable is connected for revolving said rotor to a position to display "left turn" and "right turn" signal indicia, electrical means actuated by the depression of a vehicle brake pedal for rotating the rotor to display "stop" signal indicia through the front and rear sight openings simultaneously, means for holding the rotor against return movement while the brake pedal is depressed and electrical means for actuating the holding means for releasing the signal rotor to permit return movement of the rotor to the position from which it was initiated after pressure on the brake pedal has been released.

5. In a traffic signal structure for application to the front of a vehicle, a casing having a sight opening extending across the entire front of the casing and having a sight opening extending across one half of the rear of the casing, a hollow globular rotor provided with a plurality of circumferentially disposed "go", "left turn", "right turn", and "stop" signal indicia mounted for rotation within said casing and normally positioned to simultaneously display the "go" signal indicia through the front and rear sight openings of the casing, said "stop" signal indicia being alternately arranged, manually actuated means for revolving the rotor in one direction for simultaneously bringing left turn signal indicia opposite the front and rear sight openings of the casing, resilient means co-acting with the manually actuated means for rotating the rotor in the opposite direction for simultaneously bringing right turning signal indicia opposite the front and rear sight openings of the casing, a foot pedal, electrically actuated mechanism controlled by depressing said pedal for revolving the rotor to simultaneously bring "stop" signal indicia opposite the front and rear sight openings of the casing and hold the rotor in such stop position whether the rotor displayed "go", "left turn", or "right turn" prior to rotation to display the "stop" signal indicia and means for electrically releasing the rotor from "stop" signal posi-

tion to permit return movement thereof to the position from which it was initiated.

6. In a traffic signal structure for application to the front of a vehicle, a casing having a sight opening extending across the entire front of the casing and having a sight opening extending across one half of the rear of the casing, a hollow globular rotor provided with a plurality of circumferentially disposed "go", "left turn", "right turn", and "stop" signal indicia mounted for rotation within said casing and normally positioned to simultaneously display the "go" signal indicia through the front and rear 10 sight openings of the casing, said "stop" signal indicia being alternately arranged, manually actuated means for revolving the rotor in one direction for simultaneously bringing left turn signal indicia opposite the front 15 and rear sight openings of the casing, resilient means co-acting with the manually actuated means for rotating the rotor in the opposite direction for simultaneously bringing right turning signal indicia opposite the 20 front and rear sight openings of the casing, a battery, a foot pedal, a two way switch connected with said foot pedal, a solenoid including an armature, a plunger carried by said armature, resilient means for normally 25 holding the armature in its outer position, a ratchet wheel carried by and within the rotor having its teeth disposed in the inward path of travel of said plunger, a closed 30 electrical circuit including the winding of the solenoid established through one contact 35 of the switch by depressing the brake pedal for moving the armature into the solenoid and causing the plunger to rotate the rotor to a new signal position to display "stop"

signal indicia simultaneously through the front and rear sight openings of the casing, a holding device for holding the rotor in said "stop" signal position, an electromagnet for releasing the holding device and a circuit therefor including the other contact of the two way switch, means for opening said first electric circuit and closing one break in said second circuit during inward movement of the armature and the second circuit being completed through the switch by the release of said foot pedal for actuating the holding device for releasing the rotor and permitting automatic return rotation of the rotor to its normal "go" signal position.

7. In a vehicle traffic signal, a hollow globe shaped casing having a front sight opening and a rear sight opening, a hollow globe shaped rotor having a plurality of "go" signal indicia, a plurality of "left turn" signal indicia, a plurality of "right turn" signal indicia and a plurality of "stop" signal indicia so that the signal indicia will be displayed to the front and to the rear of the case simultaneously, said latter indicia being alternately arranged and said rotor adapted to normally assume "go" position, manually actuated means for revolving the rotor from "go" position to either "left turn" or "right turn" signal position, manually controlled electrically actuated means for revolving the rotor to "stop" signal position from either "go", "left turn", or "right turn" signal position and means for returning the rotor from "stop" signal position to the signal position from which it was initiated.

In testimony whereof, I have hereunto signed my name to the specification.

WILLIAM B. HUSSAR.
